FLUID PUMP AND DISTRIBUTING DEVICE
Charles E. Sylvander, 230 Granville Road, North Granby,
Conn., and Chester J. Ducki, 885 Ratley Road, West
Suffield, Conn.

Filed Nov. 5, 1962, Ser. No. 235,399
7 Claims. (Cl. 123—139)

This invention relates to a fluid pump and distributing device therefor and more particularly to a liquid fuel supplying device for the cylinder or cylinders of an internal combustion engine.

The present invention constitutes an improvement on the fluid distributing device described and shown in our joint Patent No. 2,946,290 granted July 26, 1960.

An object of primary importance of the present invention is that the pumping device is provided with two oscillating members in a rotatable member, the oscillating members being disposed at right angles to each other, and both of which members contact an oblique end face of the pump casing similar to that shown in the above referred to patent.

Another object of importance of the invention is that a peripheral cam is mounted for rotation with the rotatable member and oscillating members of the pump which during rotation successively actuates the pistons of individual radially disposed pumps from which fluid may be admitted to individual combustion chambers of an internal combustion engine.

And finally it is an object of the invention to provide a manually or otherwise controlled valve by means of which a small variable amount of air may be added to control the increase and decrease of intake manifold pressure within the device to maintain the proper fuel to air ratio during various ranges of operation of the engine.

With the above and other objects in view, the invention may include the features of construction and operation set forth in the following specification and illustrated in the accompanying drawings.

In the accompanying drawings annexed hereto and forming a part of this specification, I have shown the invention embodied in a liquid fuel admitting device for an internal combustion engine; it will be understood, however, that the invention can be otherwise embodied and that the drawings are not to be construed as defining or limiting the scope of the invention, the claims appended to this specification being relied upon for that purpose.

In the drawings:

FIG. 1 is a longitudinal central view enlarged for clarity, partly broken away, of a fluid pumping and distributing device made in accordance with the present invention;

FIGS. 2 and 3 are side views of the oscillating disks forming the pumping members mounted for rotation with the rotatable member and oscillating during rotation of the rotatable member;

FIG. 4 is a sectional view of a valve for admitting variable small amounts of air to control the intake manifold pressure within the device;

FIG. 5 is a transverse view of the pump taken looking in the direction of the arrows on the plane of line 5—5 in FIG. 1 showing the oblique pumping end of the casing;

FIG. 6 is a transverse view similar to FIG. 5, the section being taken looking in the direction of the arrows on the plane of line 6—6 in FIG. 1;

FIG. 7 is a transverse view similar to FIG. 5, the section being taken looking in the direction of the arrows on the plane of line 7—7 in FIG. 1;

2

FIG. 8 is a transverse view similar to FIG. 5, the section being taken looking in the direction of the arrows on the plane of line 8—8 in FIG. 1;

FIG. 9 is a transverse view similar to FIG. 5, the section being taken looking in the direction of the arrows on the plane of line 9—9 in FIG. 1;

FIG. 10 is a transverse view similar to FIG. 5, the section being taken looking in the direction of the arrows on the plane of line 10—10 in FIG. 1;

FIG. 11 is a transverse view similar to FIG. 5, the section being taken looking in the direction of the arrows on the plane of line 11—11 in FIG. 1;

FIG. 12 is a transverse view similar to FIG. 5, the section being taken looking in the direction of the arrows on the plane of line 12—12 in FIG. 1, and

FIG. 13 is a transverse view similar to FIG. 5, the section being taken looking in the direction of the arrows on the plane of line 13—13 in FIG. 1.

In the above mentioned drawings, there has been shown but one embodiment of the invention, and a slight variation, which are now deemed preferable, but it is to be understood that changes and modifications within the scope of the appended claims may be made without departing from the spirit of the invention.

Referring more in detail to the figures of the drawing and first to the somewhat enlarged central longitudinal view shown in FIG. 1, it will be seen that the fluid pump comprises two principal members, a casing 10 having a cylindrical bore and a generally cylindrical member 12 rotatable therein. The casing 10 at one end is closed by a head 14, the internal surface of which is inclined relative to the axis about which the rotatable member rotates. The end of the rotatable member 12 adjacent to the inclined surface of the casing 10 is conical as shown and is provided with two deep narrow longitudinally extending semi-circular slots 16 through axial planes of the rotatable member, the slots 16 being disposed at right angles to each other.

Within the slots 16 are mounted thin disk-like members 18, their inner semi-circular edges closely fitting the inner surfaces respectively of the slots 16. To enable these disk-like members 18 to fit within and oscillate within their slots 16 without interference during operation, one has a portion of its semi-circular surface cut away and the other has a portion of its central portion removed. The outlines of these members are clearly shown in FIGS. 2 and 3.

As shown in FIG. 1 the conical end face of the rotatable member 12 has an annular flat portion 13 at its periphery which bears against an annular flat surface 15 on the casing head 14. By means of these abutting surfaces 13 and 15, which are normal to the axis of rotation of the rotatable member 12, an effective thrust bearing is provided. During rotation of the rotatable member 12 the disk-like members 18 oscillate with their outer edges in contact with the obliquely inclined flat inner surface of the casing 14. During rotation of the rotatable member 12 and oscillation of the disk-like members 18, the enclosed spaces enclosed by the disk-like members 18, the inclined surface of the casing head 14, and the end surface of the rotatable member 12 increase and decrease. This is due to the end face of the rotatable member 12 being conical, one element of this conical surface being always in contact with the inner oblique surface of the end member. During the portion of the rotation when the volume of a space is increasing, fluid is admitted thereto by the vacuum induced therein through an intake conduit 20 extending through the wall of the casing head 14. During the portion of the rotation of member 12 while the volume in a space is decreasing, the fluid within the space is forced from the space through

a discharge valve 22, one of which is provided in the rotatable member 12 for each of the spaces between the disk-like members.

The intake connection 20 as shown is mounted in the casing head and permits the fluid during rotation of member 12 to successively enter the spaces between the disk-like members 18. At its outer end the intake conduit is connected to any suitable fluid supply line not shown. To aid in the admission of fluid to the spaces between the oscillating disks an arcuate recess 21 shown in FIG. 5 is cut into the oblique inner surface of the casing head 14. By means of this arcuate channel 21 fluid may freely enter a space while the capacity of the space is increasing. The discharge valves 22, one for each chamber, are mounted in the conical end face of the rotatable member 12 and permit the fluid after passing a discharge valve 22 to enter a deep annular channel 24 in the rotatable member 12 through discharge passages 26 between the valves 22 and the channel 24. As shown in FIG. 1 the discharge valves 22 are spring pressed against their seats. Also as shown in FIG. 1 the valves 22 have their body portions longitudinally grooved to permit fluid to pass from conduit 26 through the grooves to the annular channel 24 in the rotatable member 12.

From the annular channel 24 formed in the rotatable member 12 the fluid under pressure enters a regulating valve chamber 28 through passage 30 in the rotatable member 12; after passing the regulating valve chamber the fluid enters conduits 32 and 34 in the rotatable member 12 which extends to the end face of the rotatable member 12 opposite the oblique end face of the casing 10.

To take care of any excess fluid discharged through the valves 22 to the annular recess 24 in the rotatable member 12, a relief valve 36 is provided in the casing 10 permitting fluid to enter a conduit 38 in the casing 10 after passing the relief valve. This conduit 38 leads back to the intake opening 20 from which the fluid may again enter the spaces between the disk-like members 18. As shown, the relief valve 36 is in the form of a ball, spring pressed to maintain the valve closed except when the pressure in the annular recess 24 exceeds the adjusted pressure of regulating spring. The valve chamber for valve 36 is connected to the annular channel 24 by conduit 35.

As shown in FIG. 1, in the regulating valve chamber 28 is a valve 40 mounted longitudinally within the chamber 28 and has an intermediate portion of frusto-conical form. To regulate the axial position of the regulating valve 40 and therefore the amount of its opening to conduits 32 and 34, a helical spring 37 engages its right hand end as seen in FIG. 1. The pressure of this spring may be varied by a threaded member 42 extending to the end surface of the rotatable member 12.

A plastic bellows member 44 having a central opening extending therethrough bears against the opposite or left hand end of the valve 40. This left hand end of the regulating valve chamber 28 is maintained at atmospheric pressure by means of a conduit 46 through the rotatable member 12 leading to an annular channel 48 therein. An opening 50 through the wall of the casing 10 permits air to freely enter the annular channel 48 and radial channel 46.

Rotation of the rotatable member 12 successively brings the outer end of conduit 34 into alignment with each of an annular group of small pump cylinders 52 arranged radially within a plate-like member 54 fixed to the end face of the casing member 10. Within these cylinders operate pistons 60 presently to be more specifically referred to.

Movement of the regulating valve 40 axially in its chamber 28 to vary the amount of fluid entering the chambers 52 of the individual radially disposed pumps is controlled by variations of pressure in the annular recess 61 which is connected to the intake manifold of

an internal combustion engine (not shown). When the engine is started the pressure within the intake manifold drops below atmosphere which reduced pressure operates against the right hand end of valve 40 and forces the valve 40 to the right. The pressure against the opposite end of the regulating valve remains atmospheric by reason of passage 46, channel 48 and passage 50.

With the increased speed of the engine and increased manifold pressure, the pressure against the right hand end of the regulating valve 40 increases which serves to move the valve toward the left and increase the flow of fluid past the valve to the intake conduit 34 for the individual radially positioned pistons 60 in chambers 52. From conduit 34 the fluid under pressure enters a chamber 52 through an opening or passage 62 in alignment with conduit 34. As conduit 34, during rotation of the rotatable member 12, comes into alignment with an opening 62 for each radial pump, an amount of fluid, determined by the axial position of regulating valve 40, enters a chamber 52. To permit fluid to enter an intake conduit 62 while the member 12 is rotating through an appreciable arc, a curved recess 63, as shown in FIG. 10, is cut in the end face of member 12 opposite the conduit 62.

As cam 64, rotating with member 12 to which it may be keyed as by pins 66, has a portion of its periphery cut away as shown at 68. This cut away portion of cam 64, in order to give smooth operation of pistons 60, may be in the form of an arc of a circle of greater radius than that of the full diameter of the cam. When this recessed portion 68 of cam 64 contacts piston 60 of one of the radial pumps, spring 70 moves the piston radially inward and allows admission of fluid into a chamber 52. As the member 12 and cam 64 rotate, conduit 34 passes the intake passage 62 of a pump and movement radially outward of the piston by cam 64 forces the fluid from a chamber 52 into a connection 72, one for each pump leading to the intake of one of the cylinders of an internal combustion engine (not shown).

Fluid enters one of the radial pump chambers 52 through its intake passage 62 only when the reduced portion of the rotating cam 64 is in contact with a piston 60 and the piston 60 is in contact with the decreasing radius of the recessed portion of the cam. As the rotary member 12 and cam 64 continue to rotate, the piston 60 is forced radially outward as the cam radius increases and forces the fluid from the chamber 52 into one of the admission lines 72 leading to the internal combustion engine cylinder.

The casing 10 has a head 80 secured to the containing member for the radially mounted pumps 60 through which extends the driving shaft 82 for the rotating member 12. As shown in FIG. 1 the driving shaft 82 forms an integral axial extension of the rotatable member 12.

In the operation of some forms of internal combustion engines, such as a diesel, it is desirable to provide a means of engine speed control by use of an air bleed valve as shown in FIG. 4. For this purpose a manually controlled valve 84 may be provided in a fitting 86 attached directly to the casing 10 in alignment with annular channel 61. A conduit 88 through casing 10 is in connection with passage 61 and a spring 92 normally forces valve 84 toward its seat. To admit a small variable amount of air to the annular channel 61 and intake conduit 33 the valve 84 may be moved from its seat against the pressure of spring 92.

For this purpose a pivotally mounted lever 96 in connection with fitting 86 has its inner end connected to the body of valve 84. The outer end of this lever 96 may be manually or otherwise operated to vary the opening to the chamber for valve 84 and admit air from atmosphere through the wall of fitting 86 by a central opening therethrough. To admit air to the chamber for valve 84 a small fitting 98 is provided having a conduit therethrough

connecting with a conduit leading to the chamber for valve 84.

In operation, rotation of the rotating member 12 causes the disk-like members 18 to oscillate within their grooves and discharges fluid, admitted to their chambers through intake connection 20, past the discharge valves 22 into the annular chamber 24. From this annular chamber the fluid or a portion of it regulated by the regulating valve 40, passes to the intake conduits for the radially disposed pumps 60 which are successively supplied with fluid by the rotation of the rotating member 12. From the pumps 60 the regulated amount of fluid is admitted to the engine cylinders.

We claim as our invention:

1. A fluid distributing device comprising:

a casing,
a rotatable member therein,
fluid pumping means within said casing and rotatable member,
a discharge conduit from said pumping means within said rotatable member extending to the end surface thereof remote from said pumping means,
fluid distributing pumps mounted in fixed position adjacent said end face of said rotatable member having radially movable pistons,
and a cam rotatable with said rotatable member, said cam engaging said pistons to successively actuate said distributing pumps to force fluid under pressure therefrom.

2. A fluid distributing device comprising:

a casing,
a rotatable member therein,
fluid pumping means within said casing and rotatable member,
a discharge conduit from said pumping means within said rotatable member extending to the end surface thereof remote from said pumping means,
distributing pumps mounted in fixed position adjacent said end face of said rotatable member,
a circumferential cam rotatable with said rotatable member having a portion of its periphery recessed with gradually changing radii,
and rotating means from said rotatable member and cam to successively actuate said distributing pumps.

3. A fluid distributing device comprising:

a casing,
a rotatable member therein,
fluid pumping means within said casing and rotatable member,
a discharge conduit from said pumping means within said rotatable member extending to the end surface thereof remote from said pumping means,
distributing pumps mounted in fixed position adjacent said end face of said rotatable member,
radially movable pistons for said pumps,
and a circumferential cam rotatable with said rotatable member to successively actuate said pistons and rotating means for said rotatable member and cam.

4. A fluid distributing device comprising:

a casing,
a rotatable member therein,
fluid pumping means within said casing and rotatable member,
a discharge conduit from said pumping means within said rotatable member extending to the end surface thereof remote from said pumping means,
distributing pumps for said fluid in said casing connected to said discharge conduit,
a control valve in said discharge conduit to vary the amount of fluid supplied to said distributing pumps,
said distributing pumps mounted in fixed radial position adjacent said end face of said rotatable member,
a cam rotatable with said rotatable member,
and rotating means for said rotatable member and cam to successively actuate said distributing pumps.

5. A fluid distributing device for internal combustion engines comprising:

a casing,
a rotatable member therein,
fluid pumping means within said casing and rotatable member,
a discharge conduit from said pumping means within said rotatable member extending to the end surface thereof remote from said pumping means,
distributing pumps for said fluid in said casing connected to said discharge conduit,
a control valve in said discharge conduit to vary the amount of fluid supplied to said distributing pumps,
means admitting air at engine manifold pressure against one end of said valve, to vary the opening of said control valve,
said radially disposed distributing pumps being mounted in fixed position adjacent said end face of said rotatable member,
a cam rotatable with said rotatable member,
and rotating means for said rotatable member and cam to successively actuate said distributing pumps.

6. A fluid distributing device for internal combustion engines comprising:

a casing,
a rotatable member therein,
fluid pumping means within said casing and rotatable member,
a discharge conduit from said pumping means within said rotatable member extending to the end surface thereof remote from said pumping means,
a control valve in said discharge conduit to vary the amount of fluid supplied to radially disposed distributing pumps for said internal combustion engine, means admitting air at atmospheric pressure against one end of said valve,
means admitting air at intake manifold pressure of said engine against the opposite end of said control valve, said radially disposed distributing pump being mounted in fixed position adjacent said end face of said rotatable member,
a cam rotatable with said rotatable member,
and rotating means for said rotatable member and cam to successively actuate said distributing pumps.

7. A fluid distributing device for internal combustion engines comprising:

a casing,
a rotatable member therein,
fluid pumping means within said casing and rotatable member,
a discharge conduit from said pumping means within said rotatable member extending to the end surface thereof remote from said pumping means,
distributing pumps for said fluid in said casing connected to said discharge conduit,
a control valve in said discharge conduit to vary the amount of fluid supplied to said distributing pumps for an internal combustion engine,
means admitting air at atmospheric pressure against one end of said valve,
means admitting air at intake manifold pressure of said engine against the opposite end of said control valve, and means to bleed small amounts of air at atmospheric pressure with air at manifold pressure against said opposite end of said control valve.
